UNITED STATES PATENT OFFICE.

EDWIN L. WALLACE, OF NIAGARA FALLS, NEW YORK, ASSIGNOR TO THE SHREDDED WHEAT COMPANY, OF NIAGARA FALLS, NEW YORK.

MACHINE TO FACILITATE THE USE OF CARTONS.

1,092,288.

Specification of Letters Patent. Patented Apr. 7, 1914.

Application filed October 20, 1910. Serial No. 588,089.

To all whom it may concern:

Be it known that I, EDWIN L. WALLACE, a citizen of the United States, and resident of Niagara Falls, in the county of Niagara and 5 State of New York, have made a certain new and useful Invention in Machines to Facilitate the Use of Cartons; and I declare the following to be a full, clear, and exact description of the same, such as will enable 10 others skilled in the art to which it appertains to make and use the invention, reference being had to the accompanying drawings, and to letters or figures of reference marked thereon, which form a part of this 15 specification.

Figure 1 is a side view of the left hand portion of the machine, showing mechanism for carrying cartons from the packing tables. Fig. 2 is a side view of the right hand 20 portion of the machine showing devices for sealing the cartons. Fig. 3 is a top view of mechanism shown in Fig. 1. Fig. 4 is a top view of mechanism shown in Fig. 2. Fig. 5, is a transverse vertical section through line 25 5—5 on Fig. 1. Fig. 6, is a detail perspective view showing carton in carrier link.

The invention relates to mechanism designed to facilitate the packing of biscuit, crackers or other delicate articles in cartons 30 and sealing the latter, and it consists in the novel construction and combinations of parts as hereinafter set forth.

The object of the invention is mainly to provide for a steady and even movement of 35 the charged carton, so that after it has been packed it can at once be placed in position for sealing, and will be continuously and steadily moved, and at the same time held securely in such position, throughout the operation of the mechanism and will not be subjected to irregular and rough handling, which has a tendency to break or injure the articles packed therein.

In the accompanying drawings the figure 45 1 designates a framework supporting on each side an elongated packing shelf or table 2; and centrally, above the level of said table a horizontal extension of an endless carton-carrying belt or chain 3, said belt or band 50 extending through and engaging mechanism for sealing the cartons as they are carried by said belt. The mechanism is also provided underneath and parallel to the carton carrier extension with an endless belt 4, at about 55 the level of the packing tables, for deliver-

ing the articles to the packing operatives, who sit at the tables, and an endless belt 5 for receiving and returning the pans, when such are used in the delivery, to the source of supply. The horizontal extension of the carton carrier belt is shown at 3'.

The framework 1, has substantially parallel sides, and is of elongated form in order to provide for extended mechanism whereby the articles are brought from the place of supply, along between the packing tables, through the devices for sealing the flaps of the cartons and for drying the glue, in such wise as to deliver the cartons packed and sealed for casing for transportation. The 60 carton-carrying chain 3 is therefore of considerable length, and is designed to be driven by means of a sprocket wheel E, geared up for the application of power. The chain 65 consists of links c, provided with rollers b, adapted to engage tracks a, each of said links having upright flanges c', rising from its cross-plate c², and extending transverse the machine, designed to hold the carton in position for the work to be done in connection 70 therewith, as it is moved along the mechanism.

The carton which is employed for use with this mechanism is designed to be of rectangular shape and folding character, having flaps or folding parts at its ends, these being extensions of its four walls. Of these 75 flaps or folds those which are upright in the carrier are designed to meet or be in such near proximity that the opening between 80 them can be closed by a narrow sealing strip.

The carrier chain 3 having a horizontal extension in front of the sealing devices moves lengthwise the frame, along the track a, and on the upper or direct branch thereof carries its links with their flanges projecting upward. In the lower or return branch of this chain the links are carried with their flanges depending, such lower branch being some distance below the upper branch in the sealing portion of the machine, while in the front horizontal extension of the frame the return track is immediately under the direct track, so that the return branch of the chain 85 is carried along just under the carrying branch so as not to interfere with the packing operation. The direct and return tracks gradually separate at the end of the packing mechanism, and the direct track, which is substantially horizontal, is intermitted for 90 100 105 110

6 a short distance, at 6, in order to provide for the upper portion of the sprocket wheel E, which takes the place of the track at this point in order to engage the links of the chain carrier at an intermediate point of its length. A slight downward inclination of the track just before its intermission at 6 is designed to facilitate the engagement of the carrier links with the sprocket wheel, this 10 being insured by the guide bars 14, which engage the links on their upper edges and keep them to the tracks.

When the goods to be packed are placed upon the delivery belt 4 in pans, these are 15 carried by said belt along the track arranged therefor, at the level of the packing tables 2 and between the same. This belt 4 is provided with transverse bars placed in series at a distance from each other about 20 the length of a pan, and when a pan has arrived at the end of this belt it is pushed onto a slideway S, which is operated by means of the engagement of said transverse bar with bevel ends of the tracks of the slide- 25 way, so that these open or separate to allow the pan to fall upon the return belt 5, which is also provided with transverse bars and carries the pan back to the place of charging the upper belt with the pans.

30 The biscuit or other articles taken from the belt 4 are placed by the operators seated at the lateral tables in the cartons, which are temporarily closed at their ends by folding the flaps. Each carton is then placed 35 between the flanges of a link of the horizontal extension of the carrier chain 3, traveling upon the upper track a, whereby the carton is carried, between lateral walls 7 of the frame, extending along the sides of the 40 tracks, said walls serving to hold the flaps in folded position. The carrier chain extension in its movement to that portion of the machine by which the sealing is effected, is engaged by the sprocket wheel E, and carries the carton between side walls G having 45 openings g, through which the upright flaps of the carton protrude by their elasticity, and are then held open by the wall G and spreading slides h, having motion of recipro- 50 cation, in such wise that they are in proper position for the application of glue both to the upright flaps and the cross flaps, by means of disks f, fed from glue pans 8. By 55 means of the walls G and similar reciprocating slides operating as the carton is carried along between the walls, the upright flaps are closed upon the cross flaps and the carton is carried by the chain to that portion, K, of the mechanism whereby the sealing 60 strips are applied along the upright flaps at their adjacent edges. These strips are cut from a ribbon reel R, by means of knives z, after the depending portion of each ribbon has been supplied with glue 65 upon its inner surface by means of the glu-

ing rollers V, and has been pressed upon the carton by the pressure plates 9. The portion K of the mechanism has reciprocating motion in order that it shall have even movement with the chain 3 until the sealing strip has been applied. 70

Sometimes it will happen that the operators at the packing table will omit to place a carton in a link of the carrier chain, and such link will be carried along empty. In 75 order to provide for this, at the place where the sealing strips are applied the strip feeding mechanism has a depending trip finger, operating through engagement with the top of a carton, to set such mechanism in motion. 80 As this finger will not be engaged in the case of the passage of an empty chain link the ribbon moving mechanism will not be set in operation.

After the application of the sealing strips 85 to the ends of the cartons, the latter being carried along by the chain conveyer 3, pass between the heating chambers X, in engagement with the moving pressure walls x, and in this way the glue employed in fastening 90 the carton flaps and applying the sealing strips is caused to set and dry.

Operating mechanism for opening and closing the flaps of the carton, applying the adhesive, and placing the sealing strips on 95 the carton, is described in Letters Patent No. 684,788, dated October 22, 1901, and therefore a more detailed description is not here required.

By this invention the sealing mechanism 100 is provided with a carton holding extension over the delivery belt and in close proximity thereto, so that each filled carton can be placed by the packing operator, without leaving his place at the table, in fixed position with relation to the carrier extension, whereby it will be held securely in such position while being conveyed during a continuous and steady movement of such carrier to, and through, the mechanism for operating the flaps of the carton and sealing the same. And this is effected without subjecting the carton to change of position or handling, which has a tendency to cause the 110 articles contained therein to be broken or injured by contact with its walls or with each other and thereby, as frequently happens with these delicate structures, result in wasting the material thereof, and rendering many of the cartons useless. 115

Having described the invention, what I claim and desire to secure by Letters Patent is:

1. In a machine for facilitating the use of cartons, a central longitudinal endless belt, 125 a series of uniformly separated clasping means for holding cartons in fixed relation to the belt and to each other, continuous delivery means for material to be packed in cartons, under and parallel to said series of 130

means for holding cartons, lateral vertical parallel walls for holding the cartons closed above said delivery means and extending alongside said endless belt and said series of means for holding cartons, and lateral tables for holding cartons below and alongside said delivery means.

2. In a machine for facilitating the use of cartons, a central longitudinal endless belt, a series of clasping flanges for holding cartons in fixed relative position thereon, continuous delivery means for material to be packed in cartons, under and parallel to said series of means for holding cartons,

lateral vertical parallel walls for holding the 15 carton flaps closed above said delivery means and alongside said endless belt and said series of means for holding cartons, lateral tables for holding cartons below and alongside said delivery means, and means for sealing cartons while in the holding means. 20

In testimony whereof I affix my signature, in presence of two witnesses.

EDWIN L. WALLACE.
